UNITED STATES PATENT OFFICE.

WILLIAM EDWARD WALMSLEY, OF LIVERPOOL, ENGLAND.

MACHINE FOR CLOSING CARDBOARD AND THE LIKE BOXES.

Application filed February 3, 1922. Serial No. 533,789.

To all whom it may concern:

Be it known that I, WILLIAM EDWARD WALMSLEY, subject of the King of Great Britain, residing in Liverpool, in the county of Lancaster and Kingdom of England, have invented certain new and useful Improved Machines for Closing Cardboard and the like Boxes, of which the following is a specification.

10 This invention relates to a machine for folding over or closing the end flaps of cartons or collapsible cardboard boxes such machine having been especially designed to close the end flaps of cardboard boxes having overlapping countersunk ends though with slight modifications it can be used for closing the ends of other boxes as well.

According to the present invention a main operating crank shaft is provided with a plurality of cams adapted to operate a pair of hinged abutments in predetermined sequence to one another which abutments operate on a box end held in the machine and cooperate with a pair of axially movable abutments adapted to fold in the side flaps at the end of the box.

Where the machine is designed to operate on a countersunk box-end, it is preferred to provide that the main hinged abutments are capable of moving about two virtual centres, a preliminary centre coinciding with the edge of the bottom of the box, and a second centre substantially coinciding with the interior creased edge of the countersunk bottom of the box. This may be obtained by forming the hinged abutments with a sliding face plate controlled by spring or the like elastic pressure.

It is preferred to operate the gripping means for the box, carton or blank, when in the machine from the same main operating crank so that this is brought into operation previous to the functioning of any of the folding devices and is only released subsequent to the completion of operations of this device.

This invention will be more particularly described with reference to the accompanying drawings in which:

50 Figure 1 is an outside side view of one form of construction of the machine.

Figure 2 is a corresponding front elevation with the crank handle removed.

Figure 3 is a sectional side view corresponding to Fig. 1.

Figures 4, 5, 6 and 7 are detail views.

The operating crank shaft 1, driven by power or by hand crank handle such as 2, is provided with a number of operating cams 3, 4, 5. These cams may be in the form of cam discs as shown or may be in the form of cam grooves as desired. It is preferred to use cam discs as shown, co-operating with return springs but if cam grooves are used it is preferred to interpose spring connections in the drive therefor to compensate for slight inaccuracies in workmanship of the parts and to provide for some elasticity of operations.

The shaft 1 is mounted in the side plate 6, 70 of a frame 7, adapted to be screwed or otherwise mounted on a suitable base. This frame 7, has a pivot 8, for a lever 9, the operating face 10, of which serves to clamp the inner side of the carton 11, against the 75 plate 12, of the machine to hold the carton 11, securely in its predetermined position during operation upon its end by the folding device. The arm 13, on the lever 9, is provided with a stud 14 adapted to be locked 80 in any position by rotation about its axis by means of a set screw 15. This stud 14, carries an eccentric pin 16, co-operating with the end 17 of a plate 18, sliding in a guide 19 on the frame of the machine. The stud 14, is extended as shown to form a connection with the return spring 20 the free end of which is attached to the frame of the machine as at 21. The pin 22 on the upper end of the plate 18, will consequently be held by 90 the spring 20, in contact with the operative cam 5, on the shaft 1, and this cam is so disposed on the shaft that it is the first cam to come into operation and further can either have a contour concentric with the shaft 1, for a period overlapping the period of any of the other operative cams or, alternately, as shown can serve to depress the plate 18, into operative position whereupon this plate is locked by reason of a locking 95 pin 23, engaging with a projection 24, on the plate 18. This pin 23 is mounted on a lever 25, pivoted to the frame of the machine, and is brought into operative position by a spring 26. The pin 23, is brought 100 out of engagement with the projection 24, to release the plate 18 when the other cams have completed their operative cycle.

A pin 27, on the arm 28, of the crank handle 2, in a clockwise rotation of this handle comes against a pin 29 on the lever 25 so that if the spring 26 for any reason has

not forced the locking pin 23, far enough in this lever 25, will be positively moved inwards to a predetermined extent by the pin 27 rubbing against the outside of pin 29. The same pin 27, on the completion of the revolution knocks against a pin 23' on the same lever 25 as the pin 23 to free this latter from engagement with the projection 24 to release the carton on which operations have been completed to allow for a fresh carton being inserted.

It will be noticed that the pins 23, 23', 27 and 29 are provided with eccentric surfaces so that by rotating them about their axis 15 they can be adjusted for wear.

After the carton has been held by means of the lever 9, further rotation of the clockwise handle 2, brings the cam 4, into engagement with the roller 30 on a pivoted lever 31, the end 32, of which engages with a pin 33, having an eccentric surface to allow for adjustment. This pin 33, is mounted on a rack bar 34, which is raised against a tension spring 35 and has rack teeth 36 at 20 its upper end engaging with a pinion 37, on the axis of which is mounted an abutment or folding bracket 38. This bracket 38, has a base 39, mounted on pins 40 capable of sliding in slots in the bracket 38, (Fig. 7) 25 against the action of a spring 41. The object of this can be seen from Fig. 4 as it will be noticed that the carton 11, when inserted in position in the machine lies with the upper edge of its inner side coincident with 30 the axis of rotation of the folder bracket 38. The end face of the carton therefore will be folded round its hinge-line until the edge 42 of the base 39 reaches the hinge-line 43 of the carton flap. It will then be seen 35 that further folding takes place about this line as a hinge-axis and to allow for this the base 39 has the resilient connections above mentioned with its operative abutment 38. The base 39 then hinging round the line 43, 40 in returning after folding has taken place, will not tend to lift out the outermost flap 44 of the box end.

As soon as the abutment 38 has returned to its original position being free from its 45 operative cam 4, the cam 3, will have come into contact with the end 45, of a beam 46, and will immediately afterwards also come into contact with the end 47 of a beam 48 so that these two are practically-operated simultaneously. Each of them bears at its 50 opposite end on the ends 49, 50 respectively of a pair of small levers 51, pivoted at 52, to the side of the frame, the opposite ends of 55 these short levers engaging the arms 54, of bell crank levers having hook fingers 55, and moving these levers about their pivots 60 against the action of springs 56. These hook fingers 55, engage the side flaps 57 of the box and turn these in Fig. 5.

65 After the hook fingers 55 have returned

to their normal position after the passage of the cam 3, the cam 4, will come into the range of a lever 58 pivoted at one end to the frame, whose free end 59 bears against an adjustable cam pin 60 on the rack bar 61 70 and moves this down against the action of a spring 62, consequently turning the pinion wheel 63 about the axis of which the abutment 64 is pivoted having a plate 65 capable of motion relatively to it against a 75 spring 66, Fig. 6 in similar manner to the plate 38 already described. This completes the closing of the box and as shown by Fig. 6.

In certain cases it will be desirable to 80 gum the flap of the front side base piece forming the countersunk end. This may be effected automatically by the hinged abutment 38. The abutment 38 will then in its passage move against a plate 67 pivoted at 85 68 to a bracket carrying a gum trough 69 so that as the front side base-piece 70 of the box is pressed down by the plate 39 and its flap 44 is brought against the gum roller 72 and pressed against this roller by the end 74 90 of the pivoted plate 67. A guard 75 just below the gum roller is provided to prevent the back side piece of the carton 45, from coming into contact with the said gum roller. As the pinion 37 rotates it carries 95 with it a cam segment 76 which moves against an adjustable cam pin 77 on a finger 78 which supports the axis of the gummed roller 72 and allows this to swing about a pivot 79. The joint between the gum roller 100 72 and the opening in the gum trough 69 is ordinarily maintained by a spring (not shown) pressing against the gum roller. The periodic swinging of the gum roller 72 in its arcuate guides against spring 105 action allows the feeding of small charges of gum from the trough 69 on to the roller.

The gum roller 72 is rotated through a small arc once during each complete box closing operation by the action of a pawl 84 110 mounted on a sleeve 83 which is loosely mounted about the axis of the gum roller. The sleeve 83 has two arms approximately at right angles to each other, the arm 86 carrying a loose gravity or spring controlled pawl 84, while the other arm 82 is rotated by a projection 81 mounted on the rack bar 34. Therefore it will be seen that each upward movement of the rack bar 34 carries the pawl 84 against the action of a 115 spring (not shown) ready to engage the ratchet teeth on the gum roller and when the rack bar 34 falls it allows the gum roller to be fed round by the return spring to present a fresh surface to the flap 44 in readiness for the time when this will pass it shortly afterwards. A stop 87 is provided on the side of the frame for the arm 82.

I declare that what I claim is—
1. A machine for closing cardboard boxes 130

comprising in combination means to clamp the box, folding abutments engaging flaps forming the ends of the box consecutively, a moving shaft and cams on said shaft to 5 operate said folding means consecutively.

2. A machine for closing cardboard box ends comprising in combination means to clamp the box, folding abutments engaging flaps forming the ends of the box consecutively, a moving shaft, cams on said shaft to 10 operate said folding means consecutively, and means on said shaft for releasing the box from engagement in the machine.

3. A machine for closing cardboard box ends, comprising in combination means to clamp the box, folding abutments engaging flaps forming the ends of the box consecutively, a rotary shaft, a crank rotating said shaft, cams on said shaft to operate said 15 folding means in sequence.

4. A machine for closing cardboard box ends comprising in combination spring clamping means for the box, folding abutments engaging flaps forming the ends of the box consecutively, a rotary shaft, a crank rotating said shaft, cams on said shaft to 20 operate said folding means in sequence.

5. A machine for closing cardboard box ends comprising in combination spring clamping means for the box, folding abutments engaging flaps forming the ends of the box consecutively, a moving shaft cams on said shaft to operate said folding means consecutively, and means to apply adhesive 30 automatically to a flap in the course of folding.

6. A machine for closing the ends of cardboard boxes including a folding abutment engaging the closing flap of the box, means to turn said abutment about an axis coincident with the edge of the box and means to displace the operative part of said abutment relatively to a line displaced from but 40 parallel with said edge.

45 7. A machine for folding cardboard box ends comprising means to temporarily clamp the box in position, means to swing the folding abutment about the lower edge of the box, means to displace said abutment in its own plane on further rotation about said edge.

8. A machine for closing the ends of cardboard boxes comprising means to clamp the

box in the machine, folding abutments adapted to engage with the flaps of said 55 box, hinge pivots carrying said folding abutments and coaxial with the lower edges of said box and folding flaps on said folding abutments capable of sliding relatively thereto.

9. A machine for closing the ends of cardboard boxes comprising means to clamp the box in the machine, folding abutments adapted to engage with the flaps of said 60 box, hinge pivots, carrying said folding abutments and coaxial with the lower edges of said box, folding flaps on said folding abutments capable of sliding relatively thereto, and spring means restraining said flaps from sliding relatively to said abutments.

10. A machine for closing the ends of cardboard boxes comprising means to clamp the box in the machine, folding abutments adapted to engage with the flaps on said box, 75 hinge pivots carrying said folding abutments and coaxial with the lower edges of said box, folding flaps on said folding abutments capable of sliding relatively thereto, spring means restraining said flaps from sliding 80 relatively to said abutments, an operating shaft and cams on said shaft adapted to operate said abutments in sequence.

11. A machine for closing the ends of cardboard boxes comprising means to clamp 85 the box in the machine, folding abutments adapted to engage with the flaps on said box, hinge pivots carrying said folding abutments and coaxial with the lower edges of said box, folding flaps on said folding abutments capable of sliding relatively thereto, spring means restraining said flaps from sliding 90 relatively to said abutments, an operating shaft, cams on said shaft adapted to operate said abutments in sequence and 95 return springs connected to said abutments to return them to initial position subsequent to operation by said cams.

In witness whereof, I have hereunto signed my name this 23rd day of December 100 1921, in the presence of two subscribing witnesses.

WILLIAM EDWARD WALMSLEY.
